ROBERT JARVIS SMOOTHERS, OF HOLYOKE, MASSACHUSETTS, ASSIGNOR TO JAMES T. ROBINSON, OF HOLYOKE, MASSACHUSETTS.

PRINTING-PLATE ROLL.

Application filed September 11, 1925. Serial No. 55,806.

This invention relates to a plate roll for printing and is designed primarily for use in connection with plates for textile and wall paper printing, but it is to be understood that a roll, in accordance with this invention, can be employed for any purposes for which it is found applicable, and the invention has for its object to provide, in a manner as hereinafter set forth, a plate roll adapted to have detachably secured thereto a printing plate in cylindrical form and with the roll having means engaging with the plate for maintaining the opposed edges of the latter in abutting, overlapping engagement, to provide for the matching of the free edges of the design on the plate whereby a continuous design is set up for printing upon fabric or wall paper.

As is well known in textile or wall paper printing, the design is an inherent part of a printing roll, and to produce the same, the roll which is generally in the form of a hollow copper body, although in some instances it is in the form of a solid copper cylindrical body, has the periphery thereof engraved or otherwise provided throughout with the design or a portion thereof that is to be printed on the material. After the printing operation the engraved roll is discarded, but in some instances smoothed off to enable the engraving on the periphery thereof a new design or a portion thereof, and which method entails considerable time, expense and loss. A roll, in accordance with this invention, is designed to have a printing plate detachably secured thereto and after the plate has been used, it is removed from the roll and the latter can be again employed for other plates. Therefore a roll, in accordance with this invention, overcomes the expensive engraving step, as well as discarding or smoothing off of the roll, and under such circumstances operating costs are materially reduced.

The plate roll, forming the subject matter of this application, is designed as an improvement upon the plate roll as disclosed in my application S. N. 728,425, filed Jan. 22, 1925, and the roll, in accordance with this invention, overcomes the necessity of welding the bendable plate to the roll body, as the latter includes means co-

acting with means carried by the bendable plate whereby the latter is detachably connected to in enveloping position with respect to the roll body. 55

Further objects of the invention are to provide, in a manner as hereinafter set forth, a plate roll which is simple in its construction and arrangement, strong, durable, compact, thoroughly efficient and convenient in its use, readily installed in a press, quickly assembled to maintain the printing plate in position thereon, as well as quickly disassembled to provide for the removal of the printing plate, and comparatively inexpensive to manufacture. 60

With the foregoing and other objects in view, the invention consists of the novel construction, combination and arrangement 70 of parts, as hereinafter more specifically described and illustrated in the accompanying drawings, wherein is shown an embodiment of the invention, but it is to be understood that changes, variations and modifications can be resorted to which come within the scope of the claims hereunto appended. 75

In the drawings wherein like reference characters denote corresponding parts throughout the several views:— 80

Figure 1 is an elevation of a plate roll in accordance with this invention.

Figure 2 is an end elevation thereof.

Figure 3 is a fragmentary view, in longitudinal section, illustrating one end of a plate roll. 85

Figure 4 is a section on line 4—4 Figure 1.

Figure 5 is a cross sectional view of a plate roll showing the printing plate attached in position thereon. 90

A printing plate, which is to be employed in connection with a plate roll in accordance with this invention, is illustrated in section in Figure 5 and as applied to the roll body. The printing plate is indicated at 1 and consists of a body portion of sheet metal of the desired thickness and which has its outer face 2 provided in any suitable manner with a design, not shown, which is to be printed upon the material operated on. The design is so disposed on the plate that when the latter is bent in the 95 100

form of a true cylinder and secured to the plate roll, the free edges of the design will be matched to form a continuous design which is to be printed on the material or transferred to be printed on the material during the operation of offset printing. The horizontal edges of the plate 1 are bevelled, as at 3, 4, so that when the plate is in the position shown in Figure 5, the said edges not only abut, but will overlap to provide for the matching of the free edges of a design whereby a continuous design is set up. The bevelled edge 3 extends at an inward inclination whereas the bevelled edge 4 extends at an outward inclination, or in other words, the bevels are disposed in parallel incline planes to provide for the positioning of the edges in the manner as heretofore set forth, when the edges are mounted on the plate roll. Secured to each end of the plate 1, at the inner face thereof, and flush with the bevelled edges 3, 4 is a pair of attaching bars 5, 6 which extends from one side edge to the other side edge of the plate 1. The bar 5 is of less width than the bar 6, but both bars are of the same height and length. The inner face of the bar 5 is inclined or bevelled throughout upon the same plane and the outer face of the bar 5 is formed upon vertical and inclined planes, intercepting each other. The bevelled and straight portions on the outer face of the bar 5 are indicated at 8, 9 and the bevel 8 forms a continuation of the bevelled edge 3. The bar 6 has its inner face bevelled or inclined, which extends in the same plane throughout and the outer face of the bar 6 has the outer portion thereof bevelled or extending upon an inclined plane and which forms a continuation of the bevelled edge 4. The inner portion of the outer face of the bar 6 is straight and when the plate is connected to the roll body said inner portion is positioned in a plane parallel to the plane of the horizontal diameter of the roll.

A plate roll in accordance with this invention comprises a body portion formed of two semi-cylindrical sections and means coacting with the ends of said sections for maintaining them in abutting engagement. One of the sections of the roll body is generally referred to by the reference character 13 and the other by the reference character 14. As both sections of the roll body are of like construction, but one will be described, as the description of one will apply to the other. Each roll body section is formed with a reduced extension at each end and each extension is formed of an inner portion 15 having a tapered periphery 16. Each of said extensions further include a reduced semi-cylindrical portion 17 provided with peripheral threads 18. A semi-cylindrical portion 17 merges in the

outer end of the tapered portion 16. When the extensions of the section 13 are arranged in coacting relation with respect to the extensions of the section 14, the tapered portion 15 of an extension of the section 13 ⁷⁰ forms a continuation of the tapered portion 15 of the section 14 and this statement also applies to the reduced portion 17 of the section 13 with respect to the reduced portion 17 of the section 14. ⁷⁵

The inner face of the section 13 is formed with a series of spaced sockets 19, and in which are adapted to extend, when the roll sections are in abutting engagement, holding pins 20 which are secured to and project from the inner face of the section 14. The pins 20 when engaged in the sockets 19 prevent the sections 13 and 14 from shifting relatively to each other. ⁸⁰

The inner face of the section 13 is cut away to provide a triangular shaped pocket 21 which opens at the periphery of said section, and the section 14, at its inner face is cut away to provide a triangular shaped pocket 22 which opens at the periphery of the section 14. The pockets extend from one end to the other end of said roll sections and are of the same depth, but the pocket 22 is of greater width than the pocket 21 throughout. The pocket 21 is adapted to receive the attaching bar 5 and the pocket 22 the attaching bar 6. The width of the inner end of the attaching bar 5 is less than the width of the pocket 21 at its inner end. When the attaching bar 5 is mounted in the pocket 21 the inclined face 7 thereof abuts against the inclined wall 23 of the pocket 21. The attaching bar 5 when mounted in the pocket 21 does not extend completely over the bottom of the pocket 21. The attaching bar 6 is of a width greater than the width of the pocket 22 and in said pocket is mounted said bar 6. When the roll sections are held in abutting engagement, the attaching bar 6 enters pocket 21 and seats on the bottom thereof, as well as abuts against the outer face of the bar 5, see Figure 5. The attaching bars 5 and 6 coact with the pockets 21 and 22, to couple or secure the plate 1 to the roll body in the manner as shown in Figure 5. By shifting the roll sections 13 and 14 to a position so that the inner faces thereof will extend at an inclination with respect to each other, the attaching bars 5 and 6 can be removed from the pockets 21 and 22 whereby the plate 1 can be shifted from off the roll body. ⁹⁵

As before stated, means are arranged at each end of the sections of the roll body, for the purpose of maintaining them in abutting engagement, whereby the plate 1 when connected with the roll body by the attaching bars and pockets, will be secured thereto, so that the plate can be used for printing purposes. The means at each end of the sec- ¹¹⁰

¹²⁰
¹²⁵
¹³⁰

tions of the roll body prevent the separation thereof, when in abutting position, and under such conditions prevent any outward movement of the plate 1 with respect to the roll body. The means which is arranged at each end of the roll body, coacts with the threaded portions 17 and the tapered portion 15 for securely maintaining the sections 13 and 14 in abutting position, as illustrated in Figure 3. The securing means at one end of the roll body is the same as the other end, and only one of the said means will be described, as the description of one will apply to the other.

15 Each of the said securing means consists of a spindle 24, of substantial length, and which at its inner end is formed integral with a cylindrical head 25 of materially greater diameter than the spindle 24. Formed integral with the head 25, is an annular cap piece 26 having a portion of its inner face bevelled as at 27 and the remaining portion threaded as at 28. The flaring portion 27 is plane and wedges against the plane tapered peripheral face of a pair of abutting portions 15 and the threads 28 on the inner face of a cap 26 engage with the threads 18 on a pair of abutting portions 17, see Figure 3. The securing means, at each end of the roll body, may be termed coupling members and not only connect or secure the sections 13, 14 together, due to the threaded engagement of the coupling members with the part 17. The bevelled portion 27 of the cap acting upon the tapered portions 15 set up a wedging or binding action so that the sections 13 and 14 will be held abutting against each other throughout.

40 After the plate 1 has been used, it is removed from the sections 13, 14, and the roll body can then be employed for other plates. The connecting of the plate to the roll body in the manner as stated, sets up the plate in the form of a true cylinder and with the opposed edges of the plate in abutting, overlapping engagement, to provide for the matching of the free edges of a design whereby a continuous design is set up when printing.

45 As the plate is constructed independently of the roll, after the plate has been used, it does not necessitate the discarding or smoothing of a roll for when the plate is removed from the roll another plate can be immediately attached thereto.

50 It is thought that the many advantages of a plate roll, in accordance with this invention, for use in connection with plates for textile and wall paper printing can be readily understood from the foregoing description taken in connection with the accompanying drawings, and although the preferred embodiment of the invention is as illustrated and described, yet it is to be under-

stood that changes in the details of construction can be had which will fall within the scope of the invention as claimed.

What I claim is:—

1. A plate roll comprising a body portion 70 formed of a pair of sections adapted to be detachably secured together in abutting engagement and each having the inner face thereof provided with a lengthwise extending pocket for the reception of an attaching bar carried at one end of a bendable printing plate for connecting the plate in cylindrical form against said body portion when said sections are in abutting engagement, and means engaging with the ends of said sections when in abutting engagement for detachably securing said sections together. 75

2. A plate roll comprising a body portion 80 formed of a pair of sections adapted to be detachably secured together in abutting engagement and each having the inner face thereof provided with a lengthwise extending pocket for the reception of an attaching bar carried at one end of a bendable printing plate for connecting the plate in cylindrical form against said body portion when said sections are in abutting engagement, and means engaging with the ends of said sections when in abutting engagement for detachably securing said sections together. 85

90 3. A plate roll comprising a body portion 95 formed of a pair of sections adapted to be detachably secured together in abutting engagement and each having the inner face thereof provided with a lengthwise extending pocket for the reception of an attaching bar carried at one end of a bendable printing plate for connecting the plate in cylindrical form against the body portion when said sections are in abutting engagement, and means engaging with the ends of said sections when in abutting engagement for detachably securing said sections together, 95 and said sections having interengaging means to prevent one shifting relatively to the other when in abutting engagement. 100

105

4. A plate roll comprising a body portion 110 formed of a pair of sections adapted to be detachably secured together in abutting engagement and each having the inner face thereof provided with a lengthwise extending pocket for the reception of an attaching bar carried at one end of a bendable printing plate for connecting the plate in cylindrical form against the body portion when said sections are in abutting engagement, and means engaging with the ends of said sections when in abutting engagement for detachably securing said sections together, 110 and each of said pockets of the same length as the length of a section and of triangular contour. 115

120

125 5. A plate roll comprising a body portion 130 formed of a pair of sections adapted to be detachably secured together in abutting engagement and each having the inner face thereof provided with a lengthwise extending pocket for the reception of an attaching bar carried at one end of a bendable printing plate for connecting the plate in cylindrical form against said body portion when said sections are in abutting engagement, and means engaging with the ends of said sections when in abutting engagement for detachably securing said sections together, and said sections having interengaging means to prevent one shifting relatively to the other when in abutting engagement, and each of

said pockets of the same length as the sections and of triangular contour.

5. A plate roll comprising a body portion formed of a pair of semi-cylindrical sections 5 adapted to be detachably secured together in abutting engagement and each having its flat face thereof provided with a lengthwise extending triangular shaped pocket for the reception of an attaching bar carried at one 10 end of a bendable printing plate for connecting the plate in cylindrical form against said body portion when said sections are in abutting engagement, each of said pockets of triangular contour throughout, and means 15 engaging with the ends of said sections when in abutting engagement for detachably securing said sections together.
6. A plate roll comprising a body portion formed of a pair of semi-cylindrical sections 20 adapted to be detachably secured together in abutting engagement and each having a flat face thereof provided with a lengthwise extending triangular shaped pocket for the reception of an attaching bar carried at one 25 end of a bendable printing plate for connecting the plate in cylindrical form against said body portion when said sections are in abutting engagement, each of said pockets of triangular contour throughout, and means 30 engaging with the ends of said sections when in abutting engagement for detachably securing said sections together, each of said pockets opening at the inner face and at the periphery of a section.
7. A plate roll comprising a body portion formed of a pair of semi-cylindrical sections 35 adapted to be detachably secured together in abutting engagement and each having a flat face thereof provided with a lengthwise extending triangular shaped pocket for the reception of an attaching bar carried at one 40 end of a bendable printing plate for connecting the plate in cylindrical form against said body portion when said sections are

in abutting engagement, each of said pockets 45 of triangular contour throughout, and means engaging with the ends of said sections when in abutting engagement for detachably securing said sections together, each of said pockets opening at the inner face and at the 50 periphery of a section, one of said pockets being of greater width than the other.

8. A plate roll comprising a body portion formed of a pair of detachably connected abutting sections provided on their inner 55 faces with means opening at the periphery of said body portion to receive attaching bars of a bendable metallic plate for detachably connecting the latter in cylindrical form on said body portion, and means for 60 detachably connecting said sections in abutting engagement, and interengaging means provided on the inner faces of said sections to prevent the shifting of one relative to the other when the sections are in opposed 65 relation.

9. A plate roll comprising a body portion formed of a pair of detachably connected abutting sections provided on their inner 70 faces with means opening at the periphery of said body portion to receive attaching bars of a bendable metallic plate for detachably connecting the latter in cylindrical form on said body portion, and means for 75 detachably connecting said sections in abutting engagement, and interengaging means provided on the inner faces of said sections to prevent the shifting of one relative to the other when the sections are in opposed 80 relation, each of said sections being 85 semi-cylindrical in contour and the means on the inner face of each section opening at the periphery of the sections consisting of a lengthwise extending pocket of triangular contour.

In testimony whereof, I affix my signature hereto.

ROBERT JARVIS SMOTHERS.
